[57] CLAIM

The ornamental design for a portable personal computer, as shown and described.

DESCRIPTION

FIG. 1 is a right rear and bottom perspective view of the portable personal computer;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof;
FIG. 7 is a bottom plan view thereof;
FIG. 8 is a right front and top perspective view thereof in the opened position;
FIG. 9 is an exploded right front and top perspective view thereof wherein the display is removed;
FIG. 10 is a right side elevational view of the portable personal computer in the opened position;
FIG. 11 is a left side elevational view thereof;
FIG. 12 is a front elevational view thereof;
FIG. 13 is a rear elevational view thereof;
FIG. 14 is a top plan view thereof;
FIG. 15 is a bottom plan view thereof; and,
FIG. 16 is a top front and side perspective view thereof shown in the closed position.
FIGS. 8 and 9 are drawn on a reduced scale.
